SHIPPING BASKET

Filed May 12, 1924

FIG. I.

FIG. II.

FIG. III.

FIG. IV.

INVENTOR

Harry C. Link

Chappell Deard
ATTORNEYS

UNITED STATES PATENT OFFICE.

HARRY C. LINK, OF TRAVERSE CITY, MICHIGAN.

SHIPPING BASKET.

Application filed May 12, 1924. Serial No. 712,733.

To all whom it may concern:

Be it known that I, HARRY C. LINK, a citizen of the United States, residing at Traverse City, county of Grand Traverse, State of Michigan, have invented certain new and useful Improvements in Shipping Baskets, of which the following is a specification.

This invention relates to improvements in shipping baskets.

The main objects of the invention are:

First, to provide an improved shipping basket for fruit, vegetables and the like which facilitates the packing of the fruit and the packed fruit has an attractive appearance when the cover is removed.

Second, to provide an improved shipping basket having the above advantages which is very strong and durable and permits a plurality of the filled baskets being arranged in super-imposed relation without injury to the baskets or to the contents.

Objects pertaining to details and economies of my improved shipping basket will definitely appear from the detailed description to follow.

I accomplish the objects of my invention by the devices and means described in the following specification. The invention is clearly defined and pointed out in the claims.

A structure which is a preferred embodiment of my invention is clearly illustrated in the accompanying drawing forming a part of this application, in which:

Fig. I is a perspective view of my improved shipping basket.

Fig. II is a fragmentary side elevation, partially in vertical central section, the contents being indicated by dotted lines.

Fig. III is an inverted detail section illustrating the manner of packing the receptacle.

Fig. IV is a perspective view of the bottom before it is applied to the receptacle.

In the drawing similar reference numerals indicate similar parts in all of the views.

Referring to the drawing, my improved basket comprises a body 1 formed as a complete unit of longitudinal staves 2, inner and outer bottom hoops 3 and 4 and outer and inner top hoops 5 and 6. I also preferably provide an intermediate outer hoop 7. These hoops are suitably stapled or "stitched" to the staves, the body being preferably downwardly tapered as illustrated.

The bottom 8 comprises a rim or outer

hoop 9 with crossed staves 10 secured thereto. This bottom is adapted to fit within the bottom hoop of the body unit as indicated by dotted lines in Fig. III and is secured therein by means of the bendable fasteners 11, these fasteners being secured to the bottom hoops of the body and folded inwardly over the rim, thereby supporting the bottom within the lower end of the body.

The cover comprises a rim or outer hoop 12 having the crossed bowed staves 13 secured thereto, the staves being outwardly bowed thereby providing a crowned cover. This cover is detachably secured as by means of the slat 14 arranged across the cover and through the handles 15 thereof.

With the parts thus formed and arranged the cover is attached and the receptacle inverted to permit the contents being packed from the bottom of the receptacle, the top layer of articles packed, as indicated at 16 in Fig. III, being arranged with as much care as desired, the receptacle then being filled and the bottom applied and secured. The receptacle is then inverted and handled as may be desired.

With the cover thus formed the fruit is packed in an arched or crowned relation at the center so that in handling, even though the contents should "shake down" the basket still has the appearance of being well filled. Further, the crowning of the cover adds greatly to its strength so that a plurality of the loaded baskets may be arranged one upon the other without crushing the lower covers.

Having thus described my invention what I claim as new and desire to secure by Letters Patent is:

1. In a receptacle, the combination of a body unit comprising staves and top and bottom hoops, a bottom unit comprising a rim and crossed slats secured thereto, said bottom unit being adapted to be disposed within the bottom hoop of said body unit, said body unit being provided with bendable fasteners engageable with said rim of said bottom unit for securing the same in position, and a cover unit comprising a rim and crossed outwardly bowed slats secured thereto, coacting as specified.

2. In a receptacle, the combination of a body unit comprising staves and top and bottom hoops, a bottom unit comprising a rim and crossed slats secured thereto, said bottom unit being adapted to be disposed

and secured within the bottom hoop of said body unit, and a cover unit comprising a rim and crossed outwardly bowed slats secured thereto, coacting as specified.

- 5 3. A receptacle of the class described comprising a downwardly tapered body unit open at both ends, a bottom, means for securing said bottom within the lower end of said body unit after the receptacle has 10 been packed in inverted position, a cover comprising a rim and a plurality of outwardly bowed crossed slats secured thereto, and means for detachably securing said cover to said body unit.
- 15 4. A receptacle of the class described comprising a body unit open at both ends, a bottom, means for securing said bottom to

said body, a cover comprising a rim and a plurality of outwardly bowed crossed slats secured thereto, and means for detachably 20 securing said cover to said body unit.

5. A receptacle of the class described comprising a body formed as a complete unit, a bottom formed as a separate complete unit, means for securing the bottom within the lower end of said body after the receptacle has been packed in inverted position, a crowned cover formed as a complete unit, and means for detachably securing 25 said cover to said body.

In witness whereof I have hereunto set my hand.

HARRY C. LINK. [I. S.]
